UNITED STATES PATENT OFFICE.

HENRY G. VOIGHT, OF NEW BRITAIN, CONNECTICUT, ASSIGNOR TO SARGENT & COMPANY, OF NEW HAVEN, CONNECTICUT, A CORPORATION OF CONNECTICUT.

LOCK.

1,294,208.

Specification of Letters Patent. Patented Feb. 11, 1919.

Application filed July 17, 1918. Serial No. 245,384.

To all whom it may concern:

Be it known that I, HENRY G. VOIGHT, a citizen of the United States, residing in New Britain, county of Hartford, and State of Connecticut, have invented certain new and useful Improvements in Locks, of which the following is a full, clear, and exact description.

This invention relates to locks and more particularly to pin tumbler locks which are intended to operate elements under the oily greasy conditions hereinafter set forth.

The construction of the ordinary pin tumbler lock is such that if a considerable amount of grease or oil is permitted to reach the pin tumblers, it will interfere with the proper operation of the small sliding pin tumblers rather than improve the operation of the lock as might be expected. The pin tumblers normally slide free within the pin tumbler sockets and are usually forced toward the key barrel by a very light coiled spring. If the relatively heavy oil such as is commonly found about the bearings of an automobile is permitted to work its way into a cylinder lock, it will tend to cause the pin tumblers to stick in their sockets and thereby seriously interfere with their proper operation.

One object of my invention is to provide a cylinder lock with simple but efficient means for preventing oil and foreign matter from working its way into the lock casing around the key barrel.

Another object of my invention is to provide yielding means for retaining a key barrel in its unlocked position whereby the jolts and jars to which the lock may be submitted will be prevented from causing the key barrel to rotate.

Still another object of my invention is to improve the means for operatively connecting the key barrel of the cylinder lock to the bolt or the like operated thereby.

To these and other ends the invention consists in the novel features and combinations of parts to be hereinafter described and claimed.

In the accompanying drawing,

Figure 1 is a sectional view of a casting having a sliding bolt mounted therein and a cylinder lock for operating this bolt, the bolt being shown in its lowered or locked position;

Fig. 2 is a fragmentary sectional view of

the casting shown in Fig. 1, showing the cylinder lock in section and the key barrel in its unlocked position;

Fig. 3 is a rear end view of the cylinder lock showing the bolt operating means upon the inner end of the key barrel in full lines in its locked position, and in dotted lines in its unlocked position;

Fig. 4 is a rear end view of the cylinder lock with the bolt operating means removed from the key barrel; and

Fig. 5 is a sectional view taken on the line 5—5 of Fig. 2.

In the embodiment of my invention illustrated in the drawing, the numeral 10 designates a casting such as is commonly provided upon automobiles to adjustably support the gear shifting lever. In order to provide means for locking the gear transmission mechanism so that an unauthorized person will not be able to shift the gears of the automobile, I preferably provide the casting 10 with a lateral extension in which a bolt receiving socket 11 is formed, in which socket the bolt 12 is slidably mounted. The casting 10 is also preferably provided with a ring-like extension 13 in which a cylinder lock, designated in its entirety by the numeral 14, is mounted. The sliding bolt 12 may be provided with any desired means (not shown) upon its lower end for locking the transmission gears or for performing any other desired function. Since it is necessary to keep the transmission gears and all other elements of the transmission mechanism well greased or oiled, this grease or oil necessarily works its way up the sliding bolt 12 and, if not prevented, will work its way into the interior of the cylinder lock 14. If this oil or grease is permitted to reach the interior of the cylinder lock, it will seriously interfere with the proper operation of the pin tumblers, as above pointed out.

One object of my invention therefore, as above stated, is to prevent grease, oil and other foreign matter from working into the cylinder lock about its key barrel. The usual construction by which the bolt 12 locks the transmission gears or other elements against movement is such that when the key barrel is rotated to its locked position, the bolt 12 operated thereby is moved downward to the position shown in Fig. 1 into locking engagement with the element 110

controlled by the lower end of this bolt, and when the key barrel is turned to its unlocked position, the bolt is raised as shown in Fig. 2, in which position its lower end is out of locking engagement with the element engaged thereby. It will therefore be seen that when the automobile is operated, the bolt 12 is in the raised position shown in Fig. 2, and the key barrel is turned to its unlocked position. Due to the fact that this bolt 12 is supported in substantially a vertical position by its key barrel when the bolt is in its inoperative position and when the car is being operated, the jolts and jars to which the parts of the car are submitted under normal running conditions will tend to shake this bolt 12 in a downward direction and thereby tend to cause the key barrel to rotate from its unlocked to its locked position.

In order to avoid the objectionable features above referred to, the cylinder lock 14 in the particular form shown, consists of the usual casing 15, escutcheon or face plate 16 which rests upon the outer edge of the ring-like portion 13 of the casting 10, and of the usual key barrel 17 and pin tumblers 18. The inner end of the key barrel 17 preferably extends a short distance beyond the inner face of the casing 15 and upon this inner end is mounted an eccentric disk 19, this disk preferably having a socket formed in its inner face to receive the projecting inner end of the key barrel, and is rigidly secured to the key barrel by a pin 20 passing through the disk and key barrel. The eccentric disk 19 has operative engagement with a notch 19' formed in a lateral face of the bolt 12, the construction being such that when the key barrel is rotated, the eccentric disk rotates in the notch 19' and moves the bolt 12 in a longitudinal direction. The engagement between the eccentric disk and the notch 19' serves also as means for preventing the bolt 12 from rotating within its socket 11. In the inner face of the casting 15 is formed a circular groove or shallow socket 21 concentric with the drill hole in this casing, in which the key barrel is rotatably mounted, and in this groove or socket is preferably mounted a washer 22, formed of felt or of any other suitable fabricated material which will tend to prevent oil and grease from working into the lock case 15 about the key barrel. By forming a socket in the inner face of the eccentric disk 19 instead of forming a drill hole entirely through this disk to receive the protruding end of the key barrel 17, oil is excluded from the inner end of the key barrel, and since the washer 22 is of sufficient width to contact with the inner face of the disk 19, oil and grease are very effectively excluded from the interior of the

cylinder lock by the construction just described.

In order to prevent the key barrel from being gradually rotated from its unlocked to its locked position by the weight of the bolt 12 and the jolt and jarring to which all parts of an automobile are submitted under running condition, I form a socket 23 in the lock casing 15 somewhat similar to the sockets in which the pin tumblers 18 operate. In this socket is preferably provided a ball 24 forced toward the key barrel by a coiled spring 25. This ball 24 is positioned to engage the key slot 26 formed in the key barrel as shown in Fig. 80 5 when the key barrel is turned to its unlocked position as shown in this figure. The pressure exerted upon the ball 24 by its spring is sufficient to retain this ball in engagement with the key slot 26 under 85 normal conditions, and thereby prevent the key barrel from rotating, but the pressure exerted by this spring is not sufficient to prevent the key barrel from being easily rotated manually from its unlocked to its 90 locked position when it is desired to move the bolt 12 from its unlocked to its locked position.

In order to provide means by which the key 27 may be removed from its key barrel 95 when the latter is turned to its unlocked position, shown in Fig. 2, I form a trough, such as 28, in the lock case 15, of sufficient depth to permit the pin tumblers 18 to move outwardly into this trough a sufficient distance to permit these pin tumblers to clear the teeth of the key in order that the same may be removed from its key barrel. This means by which the key may be removed from its key barrel while the key barrel is in its unlocked position is described more fully and claimed in the co-pending application of John H. Shaw, Serial No. 224,241. The enlarged knurled head 29 formed upon the outer end of the key barrel is provided in order that the same may be grasped by the fingers to rotate the key barrel to its locked position after the key has been removed.

From the above description, when read in connection with the drawing, it will be apparent that the ball 24 which cooperates with the key slot 26 forms a very simple but efficient means for yieldingly locking or holding the key barrel in its unlocked position, and that the washer 22 when positioned between the inner face of the lock case 15 and the eccentric disk 19 in the manner above described, forms a simple but satisfactory means for excluding oil and the like from the interior of the lock casing.

Although I have illustrated and described my improved cylinder lock as mounted upon a gear shifting bracket of an automobile to operate means for locking the transmission 130

mechanism, it will be obvious that my invention is not limited to this particular use but that the same may be used for various purposes without departing from the 5 spirit or scope of my invention.

I have not attempted to describe the modifications of the construction which may be adopted without departing from the 10 scope of the invention as defined in the annexed claims.

What I claim is:

1. In a cylinder lock, a key barrel having a key slot formed therein, and means co-operating with said key slot for yieldingly 15 holding said barrel in its unlocked position.
2. A cylinder lock comprising a case, a key barrel having a key slot formed therein, and spring operated means mounted in said case co-operating with said key slot for yieldingly holding said barrel in its unlocked 20 position.
3. In a cylinder lock, a key barrel having a key slot formed therein, pin tumblers for locking said barrel against rotation, and spring operable means engaging said key slot for yieldingly holding said key barrel in its unlocked 25 position.
4. In a cylinder lock, a case, a key barrel having a key slot formed therein, and spring operated means mounted in said case and positioned to engage said key slot to yieldingly hold said key barrel from being rotated from its unlocked to its locked 30 position.
- 35 5. A cylinder lock having a lock case, a key barrel, locking means for said key barrel, and a washer of fabricated material surrounding said key barrel to exclude foreign matter from said barrel locking means.
- 40 6. A cylinder lock having a lock case, a key barrel, locking means for said key barrel and fabricated means positioned within said case to exclude foreign matter from said barrel locking means.

7. A lock having a lock case, key operable 45 means within said case, and fabricated material within said case to exclude foreign matter from said key operable means.

8. A cylinder lock having a lock case, a key barrel, locking means for said key barrel, and a washer of fabricated material surrounding the inner end of said key barrel to prevent liquid from working into said case around the key barrel. 50

9. A cylinder lock having a lock case, a key barrel, locking means for said key barrel, bolt operating means upon the inner end of said key barrel, and a pad of fabricated material between said case and bolt operating means to exclude foreign matter from 60 said case.

10. A cylinder lock having a lock case, a key barrel and pin tumblers within said case, a bolt operating means upon the inner end of said key barrel, and a washer of 65 fabricated material between said case and bolt operating means.

11. A cylinder lock having a lock case, a key barrel and pin tumblers within said case, a bolt operating means upon the inner 70 end of said key barrel, said operating means having a socket formed therein for housing the inner end of said key barrel, and fabricated means between said case and bolt operating means for excluding foreign matter 75 from said case.

12. In combination with a sliding bolt, a cylinder lock, a key barrel within said lock, said bolt having a notch formed in a lateral face thereof, and means upon the inner end 80 of said key barrel operatively engaging said notch to operate said bolt, said notch engaging means being constructed and arranged to prevent said bolt from rotating relatively to said cylinder lock. 85

In witness whereof, I have hereunto set my hand on this 13th day of July, 1918.

HENRY G. VOIGHT.
